FRONT COVER MEANS FOR STAPLING MACHINES

Harold S. Heller, Cleveland Heights, Ohio

Application August 10, 1949, Serial No. 109,483

22 Claims. (Cl. 1—49)

1

This invention relates to stapling machines and more particularly, to a staple tacker of the type which is held in and operated by one hand of the user thereof, and in which the staples are successively driven by the force of compressed spring means bearing against a plunger to which the staple driving blade is secured for movement therewith, the plunger and the staple driving blade being manually raised for compression of the spring means by operation of a lever conveniently located adjacent the tacker handle and being automatically released for staple driving purposes.

The invention has for its primary object the provision of an improved staple tacker which is characterized by its structural simplicity, the economy of its manufacture, the ease and convenience with which its parts may be assembled and disassembled, the ready access which is afforded to all interior parts, its strong, sturdy and durable nature, the ease of its operation for staple driving purposes, and its general operating efficiency.

Further objects of the present invention, and certain of its practical advantages, will be referred to in or will be evident from the following description of a staple tacker embodying the invention, as illustrated in the accompanying drawings, in which

Fig. 1 is a perspective view of such tacker;

Fig. 2 is a longitudinal sectional view thereof;

Fig. 3 is a detail cross-sectional view of the tacker head portion, the view being on the line 3—3 of Fig. 2;

Fig. 4 is a perspective view of the tacker parts in separated or "exploded" relationship;

Fig. 5 is a view corresponding to Fig. 2, but showing the staple driving blade in an elevated position for staple driving purposes;

Figs. 6 and 7 are detail sectional views, on the lines 6—6 and 7—7 of Fig. 2, respectively;

Fig. 8 is a fragmentary rear view of the lower cover member of the tacker head portion, and the lower end portion of the guiding and bearing strip for the plunger and the staple driving blade;

Fig. 9 is a detail vertical sectional view, on the line 9—9 of Fig. 2;

Fig. 10 is a fragmentary side view, partly in elevation and partly in section, showing the staple tacker with a modified form of mechanism between the plunger and the hand lever for operation of the plunger in the staple driving operation, the parts being shown with the plunger in its normal lowered position;

Fig. 11 is a view corresponding to and showing

the mechanism of Fig. 10, the plunger being in its raised position as the result of manual depression of the hand operated lever; and

Fig. 12 is a fragmentary sectional view of the rear end of the tacker, with means for preventing accidental disconnection and release of the staple follower.

Before specifically describing the staple tacker here illustrated, it is to be understood that the invention here involved is not limited to the structural details or the particular arrangement of parts here shown, as tackers embodying the present invention may take other forms. It also is to be understood that the terminology or phraseology herein used is for purposes of description and not of limitation, as the scope of the present invention is denoted by the appended claims.

The staple tacker here illustrated, for the disclosure of the present invention, comprises a metal frame, preferably formed as a die casting, and having as integral parts thereof (a) an upright head portion 10 at its front end, said head portion being of channel shape, with the side walls 11 and 12 thereof extending forwardly and providing therebetween an elongated, correspondingly upright chamber 13 for the hereinafter described staple driving mechanism; (b) a rearwardly extending elongated base portion 14, of downwardly opening channel shape and having removably mounted therein, in the manner hereinafter described, a supporting bar 15 for a strip of adhesively united staples 16, the staple strip being normally urged forwardly along said bar by the follower hereinafter described; and (c) a handle portion having a top section 17 extending rearwardly from the head portion 10, from a point intermediate the upper and lower ends thereof, and a rear section 18 extending downwardly from the rear end of the handle top section to the base portion 14 adjacent its rear end, the rearwardly extending top section 17 of the handle portion being generally parallel with the base portion 14 and being spaced therefrom to provide an elongated opening 19 between the handle top section and the frame base portion 40 for the fingers of the operator's hand in the support and manipulation of the tacker. Preferably and as here shown, the handle top section 17 is of upwardly opening channel shape to provide a pair of laterally spaced, upright mounting flanges 20 for the hereinafter described operating means for the staple driving mechanism, and the frame head portion 10 is provided on the rear surface of its upper end section with a pair of laterally spaced rearwardly extending mounting flanges 21

55

for the hand lever 22 of said operating means, the flanges 21 of the frame head portion 10 and the flanges 20 of the frame handle section 17 preferably being, as here shown, continuations of one another.

The chamber 13 of the frame head portion 10, for the staple driving mechanism, is closed except at its lower end by a pair of upper and lower front cover members 23 and 24. In the present embodiment of the invention, the forwardly extending side walls 11 and 12 of the frame head portion 10 are provided throughout their lower end portions with a pair of forwardly projecting side wall extensions 25 and 26, upon and over which the lower cover member 24 is slidably mounted. As best shown in Figs. 4 and 7, the lower front cover member, which preferably is formed as a die casting, is of channel shape in cross section, with its side walls 27 and 28 provided along their rear ends with inwardly extending beads or ribs 29 for engagement behind the outwardly extending beads or ribs 30 with which the side wall extensions 25 and 26 are provided along their front ends. As shown in Figs. 1 and 4, the lower end portions of the side wall extensions 25 and 26 of the frame head portion 10 and the lower end portions of the side walls 27 and 28 of the lower cover member 24 are of inwardly tapering form, with the result that said cover member can be telescopically associated with said side wall extensions only by sliding said cover member upwardly therealong, as will be readily understood. Means is provided, of course, for the releasable retention of the lower cover member 24 in telescopic covering relationship with the side wall extensions 25 and 26 of the frame head portion, but such means will be later described.

Inasmuch as the upper end sections of the forwardly extending side walls 11 and 12 of the frame head portion 10 have no side wall extensions, such as the lower side wall extensions 25 and 26, the upper cover member 23, which is of channel shape in cross section and preferably formed as a die casting, not only serves as a front and top closure for the upper end portion of the head chamber 13 but also, as a means to increase the depth of said upper end portion of said chamber to correspond to the depth of the lower end portion thereof, as provided by the side wall extensions 25 and 26. The upper cover member is therefore removably secured to the upper section of the frame head portion 10 with its rearwardly extending side walls 31 and 32 in alignment or registry with the forwardly extending head portion side walls 11 and 12, the securing being effected by the use of screws 33, there being two such screws (Fig. 1) extending rearwardly through the cover member side walls into the head portion side walls and one such screw (Figs. 2, 3 and 5) extending forwardly through the rear surface of the head portion into a rearwardly extending block-like projection 34 with which the upper cover member 23 is integrally provided at its upper end to close the upper end of that portion of the head chamber 13 which is between the head portion side walls 11 and 12.

Although the lower end of the upper cover member rests upon the lower side wall extensions 25 and 26, and although said cover member is removably secured by the screws 33 to the frame head portion 10, means is here provided to longitudinally interlock the upper cover member and the frame head portion to thereby additionally

strengthen and rigidify the connection of these two parts. As here shown (see Fig. 3), said interlocking means comprises a pair of relatively small block-like lugs 35 on opposite sides of the rearwardly extending top closure projection 34 and which fit into a pair of recesses 36 in the head portion side walls 11 and 12 and also, a forwardly projecting extension 37 at the top of the frame head portion, between the side walls thereof, which overhangs or overlies a shoulder 38 of the cover member closure projection 34, a shoulder which is provided by making such projection of stepped form, as clearly shown in Figs. 2, 4 and 5. If desired, the upper cover member 23 may be provided at the lower end of its front surface with a depending flange 39 which overhangs or overlies the upper end portion of the front surface of the lower cover member 24, with said lower cover member being provided with a suitable recess 40 to receive said flange, as clearly shown in Figs. 1, 2, 4 and 5.

The means for releasably maintaining the lower cover member 24 in telescopic covering relationship with the side wall extensions 25, 26 of the frame head portion 10 comprises a simple wire spring of channel form, the side arms 41 of which lie alongside the two cover members, with the inwardly coiled or hook-shaped upper ends 42 of the spring side arms underlying the upper cover member and being secured to the frame head portion by the rearwardly extending upper cover member screws 33. As shown in Figs. 1 and 2, the middle or cross portion 43 of the spring overlies the front surface of the lower cover member 24 and has snap seating engagement in an undercut groove or slot 44 extending across said lower cover member, as clearly shown in Figs. 1 and 2. To permit the lower end portion of the spring to be readily swung forwardly and rearwardly for the securing and the removal, respectively, of the lower cover member, the spring side arms 41 may be provided with coils 45 which serve as hinges for the swinging movement of the lower end portion of the spring, as will be readily understood, preferably, the side walls of the upper cover member are provided at their rear corner portions with suitable recesses or cavities 45a to receive the side arm coils 45 of the spring, as shown in Figs. 1 and 4.

Closely fitting and slidably mounted within the head chamber 13 is a plunger 46 which is normally urged downwardly against a stop or ledge 47 in the lower end portion of the chamber 13 by a pair of coiled compression springs 48, the lower ends of which are seated in cavities 49 in the upper end portion of the plunger 46, the upper ends of said springs engaging the headed upper ends of a pair of guide pins 50 arranged within said springs, with the headed upper ends 51 of said guide pins bearing against the top end closure of the upper cover member 23, as best shown in Figs. 2 and 5. To cushion the downward impact of the plunger 46 against the stop or ledge 47, which preferably is an integral part of the frame head portion 10, a resilient pad 52 of rubber or the like may be placed on the upper surface of said stop or ledge, as shown in Figs. 2 and 5.

As shown in Figs. 2, 4 and 5, the lower front portion of the plunger 46 is recessed to receive the head or upper end portion 54 of a staple driving blade 55, the lower end of which is provided with a curved recess 56 to conform to the shape of the crowns of the staples 16. For the removable but interlocking connection of the staple

driving blade to the plunger, to effect unison movement thereof, the upper end portion 54 of said blade is here provided on its rear surface with a cross rib 57 for removable seating engagement in a cross slot or groove 58 in the front surface of the recessed lower front portion of the plunger 46. Therefore, although the staple driving blade is normally securely interlocked with the plunger for endwise reciprocatory movement therewith, the blade and the plunger may be easily and quickly disassembled and re-assembled, when desired.

To provide a smooth bearing and guiding surface for the plunger 46 and its staple driving blade in their reciprocatory movement, a metal strip, preferably of spring steel, is interposed between the vertically aligned front faces of the plunger and the staple driving blade and the generally vertically aligned rear surfaces of the upper and lower cover members 23 and 24. As here shown (see Fig. 4), said bearing and guiding strip has an upper end portion 60 lying within the upper cover member 23 and engaging at its upper end a cross rib 61 with which said cover member is provided, and an intermediate portion 62 and a lower end portion 63 lying within the lower cover member 25, the intermediate portion 62 being of somewhat greater width than the strip end portions 60, 63 and engaging at its upper end the lower ends of the side walls 31, 32 of the upper cover member. To prevent downward endwise movement of this bearing and guiding strip, the lower cover member 24 is here provided at the lower end of its rear surface with a pair of laterally spaced, inwardly converging abutment ribs 64, Fig. 8, which form a pocket for the reception and retention of the lower end portion 63 of the strip, as will be readily understood. If desired, however, the bearing and guiding strip may be riveted or otherwise secured to either the upper or the lower cover members, for disposition alongside the rear surfaces thereof as a guide and bearing element for the plunger and the staple driving blade.

The operating means for the staple driving mechanism, means by which the plunger 46 and the staple driving blade 55 are manually raised to compress the coiled springs 48 and thereby enable said springs to forcibly propel the plunger and the staple driving blade downwardly for staple driving purposes, includes a pivoted pawl 66 movable in a vertical slot 67 in the rear wall of the frame head portion 10. As shown in Figs. 2 and 5, the nose or front end 68 of the pawl normally projects into a transverse groove or slot 69 in the rear wall of the plunger 46 to thereby operatively connect the pawl and the plunger and thereby enable the pawl to raise the plunger (and the staple driving blade carried thereby) upon clockwise movement of the pawl, as viewed in Figs. 2 and 5.

In the staple tacker as illustrated in Figs. 1 to 9 inclusive, and as shown in Figs. 2 and 5, the plunger-raising pawl 66 is pivotally mounted intermediate its ends, at 70, between the front end portions of the side arms of a channel shaped lever 71, which in turn is pivotally mounted intermediate its ends, at 72, between the upright mounting flanges 20 of the handle top section 11 of the tacker frame. A leaf spring 73, secured to the lever 71 and engaging the rear end portion of the pawl 66, normally tends to swing the pawl in a counter-clockwise direction, Figs. 2 and 5, and thus resiliently maintains the pawl in proper position for cooperation of its nose or front end

68 with the plunger, as will be readily understood.

Pivotedly connected at 75 to the rear end portion of the pawl-carrying lever 71, between its side walls thereof, is the lower end of a link 76, the upper end of which is pivotally connected, at 77, to the depending side walls of a channel-shaped bracket 78 rigidly secured to the lower surface of the hand operating lever 22. Although the bracket 78 may be rigidly secured by any suitable means to the hand lever 22, the top wall of said bracket is here provided with a longitudinal slot 79 (see Fig. 4) through which projects a depending rib 80 on the lower surface of the hand operating lever 22, and by peening over or flattening out the lower edge portion of said rib, the bracket is firmly secured to the lever.

As shown in Figs. 1, 2 and 5, the hand operating lever 22 conveniently overlies the handle top section 11 of the tacker frame, with the front end of said lever being pivotally connected, at 81, to the rearwardly extending mounting flanges 21 of the frame head portion 10. Suitably connected to the upper end of the link 76 and to the rear end of the hand lever bracket 78 is a coiled tension spring 82 which normally maintains the hand lever 22 in its raised position, Figs. 1 and 2, and the toggle-forming pawl-carrying lever 71 and link 72 in the positions there shown.

For automatic release of the plunger 46 from the pawl 66 when the plunger has been raised by such pawl to a predetermined height, sufficient to compress or "load" the compression springs 48 for staple driving purposes, the pawl 66 is provided on its lower surface, between its nose or front end 68 and its pivot 70, with a cam boss 83, as shown in Figs. 2, 4 and 5.

As will be evident from Fig. 5, the engagement of the pawl cam boss 83 with the rear surface of the plunger 46 as the plunger is elevated by clockwise movement of the pawl, causes the pawl nose or front end 68 to be cammed out of the plunger slot or groove 69 when the plunger has been raised to its predetermined maximum height. Upon release of the plunger from its engagement by the pawl 66, the plunger and the staple driving blade carried thereby are driven downwardly with great force by the power of the compressed springs 48, with the staple driving blade effecting by its downward movement the severing of a staple from the front end of the staple strip and the driving of such severed staple into the work. Thus, upon depression of the hand operating lever 22, the plunger-engaging nose 68 of the pawl 66 moves upwardly and then rearwardly, for elevation and then release of the plunger, with the pawl nose returning to its normal lowermost position, upon upward return movement of the lever, for reconnection with the now lowered plunger, as will be readily understood.

One of the features of the just described operating means for the staple driving mechanism is that the final, plunger-release movement of the hand lever 22 is effected with comparatively little effort on the part of the user of the tacker. When the hand lever 22 reaches a position substantially parallel with the handle top section 11 of the tacker frame, the tension spring 82 associated with said hand lever is under maximum tension, and no increased force is thus necessary for the final plunger-release movement of said hand lever. This is, of course, of great importance for ease of operation of a staple tacker is essential, particularly in the use of the

tacker in overhead work and the like, as will be readily understood.

The staples 16, for use in the present tacker, are of the ordinary type, with pointed legs and an arched-shaped crown. The staples are adhesively united in strip form, as in usual, and are successively severed from the front end of the strip and driven into the work by the downward power movement of the staple driving blade 55.

As heretofore mentioned, the bar 15 for the support of the staple strip is arranged within the downwardly opening channel-shaped base portion 14 of the tacker frame. As best shown in Fig. 2, the front end portion of the staple supporting bar extends into the lower end portion of the frame head 10, with the front end of said bar terminating just rearwardly of the path of travel of the staple driving blade 55 and with the rear end of said bar terminating at the open rear end of the frame base portion 14.

For the support of the rear end portion of said bar, the frame base portion 14 is integrally provided with a cross web 85 (see Fig. 2), and for the support of the front end portion of said bar, the frame head portion 10 is integrally provided with a similar cross web 86, the bar resting upon said webs, as shown in Fig. 2. Between these cross webs 85 and 86, the tacker frame is open, but for such opening, a closure strip 87 is provided, the closure strip snugly fitting and closing said opening, as indicated in Figs. 6 and 9. As best shown in Fig. 6, the tacker frame is provided along the sides of this opening with shoulders 88 against which the side edge portions of the closure strip 87 are seated, with the closure strip being retained in position against the shoulders 88 and with the staple supporting bar 15 being held against its supporting cross webs 85 and 86 by screws 89 which extend upwardly through the closure strip and into the staple supporting bar.

To enable the staple supporting bar 15 to be readily located in proper position in the tacker frame and particularly with respect to the path of movement of the staple driving blade 55, the closure strip 87 is formed with a transverse rib 90 on its upper surface for seating engagement in a transverse slot 91 provided in the lower surface of said bar. Therefore, by first placing the closure strip 87 in place, in which position the upper surface of the strip is preferably flush or in alignment with the upper surfaces of the bar supporting webs 85 and 86, it is a simple matter to determine the proper location for the staple supporting bar by merely moving said bar along the upper surface of said closure strip until the rib 90 of the strip enters the bar slot 91. When this occurs, the bar will be in proper position within the tacker frame and the apertures of said bar which receive the attaching screws 89 will be in registry with the screw-receiving apertures of the closure strip. All that is then necessary is to insert and tighten the screws 89, as will be readily understood. If desired and as shown in Figs. 6 and 9, the closure strip 87 may be provided along its upper surface with a pair of longitudinally disposed, laterally spaced ribs 92, between which the staple supporting bar is slid in the positioning thereof and between which it thereafter retained.

As shown in Figs. 2, 4 and 5, the staple supporting bar 15 is here provided at its front end with a pair of laterally and oppositely extending base flanges 93 and at its rear end with corresponding flanges 94, flanges which give the bar,

of course, a more stable base. In order to insure proper positioning of the staple supporting bar within the tacker frame, the front end portion of the frame chamber for the reception of such bar is of slightly less width at the bottom thereof than the rear end portion of such chamber, and the front end flanges 93 of the bar are of slightly less lateral extent than the rear bar flanges 94. As a result, the bar can be completely inserted into the frame chamber therefor only from the rear end of the chamber and then only if the front end of the bar is inserted first.

The follower for normally urging the staple strip forwardly along the staple supporting bar, to thereby progressively feed the staples of the strip to a position in the path of movement of the staple driving blade, comprises a simple sheet metal member of inverted U-shape, which straddles the bar 15 just behind the staple strip and which is normally urged forwardly by the pressure of a coiled spring 96. As best shown in Fig. 2, the spring 96 surrounds and is carried by a rearwardly extending rod 97, the front end portion of which is slidably mounted in an upright loop portion 98 at the top of the follower member 95, with the front end of said rod being bent upwardly to prevent disassembly of the rod and the follower member. The rear end portion of the follower rod is detachably connected in any suitable manner and by any suitable means to the rear end of the tacker frame base portion, with the follower spring 96 being confined in the desired degree of compression, for effecting forward movement of the follower member, between such member and a suitable stop or abutment at the rear end of the follower rod.

As here shown, for the detachable connection of the rear end portion of the follower rod 97 to the tacker frame base portion 14, and to provide the stop or abutment for the rear end of the follower spring 96, the rear end portion of the rod is bent forwardly and then rearwardly to form a hook 99 for detachable connection to the frame base portion at the rear of an aperture 100 at the top of such base portion, with the hook 99 being yieldingly and releasably held against the frame base portion by the pressure of the follower spring 96.

To insert a staple strip into the tacker and onto the supporting bar 15 therefor, it is merely necessary to remove the follower, which is readily done by pushing the follower rod forwardly to release the hook thereof, lift the rear end portion of the rod, and then pull the follower out. After insertion of the staple strip, the follower is returned to position and the hook 99 of its rod reconnected to the frame base portion, all as will be readily understood.

Although tackers of the type here involved have wide fields of use, the tacker here illustrated is the stapling of wires, such as telephone wires, to walls, floors or other surfaces. To that end, the present tacker is so formed that it can be placed over and along the wire to be stapled, such as the wire A of Figs. 2, 6 and 9, to not only hold the wire in position but also, to insure that the securing staples will properly straddle the wire. For such purpose, the frame cross webs 85 and 86, upon which the staple supporting bar 15 rests, are located slightly above the lower edges 101 of the adjacent side wall portions of the tacker frame, with the consequent provision of wire-receiving grooves below said webs, as clearly shown in Figs. 6 and 9. The bottom end

of the lower front cover member 24 for the frame head portion 10 also is suitably grooved, as at 102, for wire-receiving purposes, as shown in Figs. 1, 4 and 8. Thus, the present tacker is of especial use to electricians and the like, although its use is not limited to the stapling of wires and if desired, the wire-receiving grooves may be eliminated.

Although the operating means for the staple driving mechanism of the tacker of Figs. 1 to 9 inclusive is considered the preferred operating means, there is illustrated in Figs. 10 and 11 a somewhat modified form of operating means for the staple driving mechanism.

In the embodiment of Figs. 10 and 11, the operating means for the staple driving mechanism comprises a plunger elevating pawl 66a having an upwardly and forwardly inclined front end portion or nose 68a for releasable seating engagement in a corresponding inclined slot or groove 69a in the rear surface of the plunger 46a. The pawl 66a is pivotally mounted at its rear end, at 70a, on the front end of a channel shaped lever 71a, with a coiled spring 73a associated with said pivot and normally tending to swing the pawl in a clockwise direction, Figs. 10 and 11, for proper cooperation with the plunger 46a. The lever 71a is pivoted intermediate its ends to the upright mounting flanges 20a of the handle top section 11a of the tacker frame, and is pivotally connected at its rear end to the lower end of a link 76a which has its upper end pivotally connected at 77a to a channel shaped bracket 78a rigidly secured to the hand lever 22a. To normally maintain the hand lever in its elevated position as in Fig. 10, a coiled spring 82a is associated with the upper pivot 77a of the link 76a, with said spring engaging the link in a manner to normally tend to straighten the toggle formed by the link 76a and the lever 71a and thus normally urge the hand lever 22a to its raised position.

To effect automatic release of the pawl 66a from the plunger 46a when the plunger has been elevated by the pawl to the desired height for compression of the plunger springs 48a, the pawl is provided on its upper surface with a cam boss 83a, and the frame head portion is provided at the upper end of its slot 67a, in which the pawl moves, with a cross pin 104 for cooperation with said cam boss. Therefore, as shown in Fig. 11, when the plunger 46a has been raised to the desired height by the pawl 66a, the pawl cam boss 83a is engaged by the frame pin 104 and the hooked-shaped pawl nose 68a is cammed out of the plunger slot 69a, with consequent release of the plunger for a staple driving operation under the power of the compressed springs 48a, all as will be readily understood from the prior and more detailed description of the operation of the tacker as illustrated in Figs. 1 to 9 inclusive.

If desired, the tacker may be provided with means for preventing accidental disconnection of the follower rod 97 from the tacker frame base portion should the tacker be dropped or the connecting hook portion 99 of the rod be otherwise struck in a manner tending to move the rod inwardly or forwardly.

Such a lock for the follower rod may be of the form illustrated in Fig. 12, a lock which comprises a simple channel-shaped lever 105 of spring steel, the lever being pivoted intermediate its ends, at 106, in a shallow cavity 107 in the rear wall of the depending rear section 18 of the

tacker handle. As shown in Fig. 12, the lower end of this locking lever is normally in abutting relation with the connecting hook portion 99 of the follower rod, so that inward release movement of the rod is prevented. However, by pressing inwardly the upper end portion of the lever, a portion which normally lies outside the handle cavity 107, the lower end of the lever is swung upwardly out of locking engagement with the follower rod, with consequent release of said rod, for its disconnection from the tacker frame, if desired.

From the foregoing description thereof, it will be quite evident that the present tacker has many features and advantages. By merely lifting out of the lower cover member groove 44 the cross portion 43 of the retaining spring for such cover member, said cover member may be readily removed from the frame head portion 10 to thereby easily, quickly and conveniently expose the front end of the staple driving bar 15, and by simple removal of the attaching screws 33, the upper cover member 23 may be readily removed, thereby exposing the entire staple driving mechanism for inspection, cleaning or repair. As shown in Fig. 2, the top portion of the frame chamber for the staples 16 is of progressively reduced size adjacent and toward the front end of the tacker, to thereby reduce the clearance space for the crowns or top portions of the staples and thereby prevent the "piling up" of staples at the front end of the tacker. As shown in Fig. 9 and also in Fig. 2, a frame groove 110 is provided, above this reduced section of the staple receiving chamber of the frame, into which the front end portion of the follower rod 97 may project when the follower is adjacent the front end of the tacker, as in Fig. 2. As a result, "piling up" of staples at the front end of the tacker is effectively prevented. The construction of the tacker parts is such as to make their assembly and disassembly easy, quick and convenient, and operation of the tacker simple and relatively easy. This is particularly true of the operation of the tacker as illustrated in Figs. 1 to 9 inclusive, wherein no added effort is necessary in the final movement of the hand lever from a position substantially parallel with the tacker handle, as there is no further elongation of the coiled spring 82 associated with said hand lever in the final movement of said lever.

To those skilled in the art to which the present invention relates, other features and advantages of tackers embodying the present invention will be obvious.

What I claim is:

1. In a staple tacker, a frame having an elongated chambered head portion for the reception of staple driving mechanism, the lower end section of the chamber of said head portion being open at its front, a front cover member for the lower end section of said chamber, and spring catch wire means on said head portion having a straight section releasably securing said cover member to said head portion.

2. In a staple tacker, a frame having an elongated chambered head portion for the reception of staple driving mechanism, the lower end section of the chamber of said head portion being open at its front, a front cover member for the lower end section of said chamber and having a slot extending across its full width, and resilient means on said head portion detachably inter-

locked with said cover member in said slot for releasably securing it to said head portion.

3. In a staple tacker, a frame having an elongated chambered head portion for the reception of staple driving mechanism, the lower end section of the chamber of said head portion being open at its front, a front cover member for the lower end section of said chamber, and resilient wire means mounted on the sides of said head portion having removable seating engagement in an undercut recess on the front of said cover member for effecting its releasable securement to said head portion.

4. In a staple tacker, a frame having an elongated chambered head portion for the reception of staple driving mechanism, the lower end section of the chamber of said head portion being open at its front, a front cover member for the lower end section of said chamber, and a U-shaped spring for releasably securing said cover member to said head portion, the side arm portions of said spring being secured to said head portion and the cross or bridge portion of said spring overlying the front wall of said cover member and being removably seated in a cross slot in such wall.

5. In a staple tacker, a frame having an elongated chambered head portion for the reception of staple driving mechanism, the lower end section of the chamber of said head portion being open at its front, a front cover member for the lower end section of said chamber, and a U-shaped spring for releasably securing said cover member to said head portion, said spring having its cross or bridge portion removably seated in a cross recess of said cover member and the side arm portions of said spring being secured to said head portion and being provided with hinge-forming coils for the movement of the cross or bridge portion of the spring into and out of the cover member recess.

6. In a staple tacker, a frame having an elongated chambered head portion for the reception of staple driving mechanism, the lower end section of said head portion being of forwardly opening channel shape in cross section, whereby the lower end section of the chamber of said head portion is open at its front, a channel-shaped front cover member for the lower end section of said chamber and having an endwise slidable telescopic connection with the channel-shaped lower end section of said head portion, and spring catch means on said head portion for releasably engaging said cover member to secure it in telescopic association with the lower end section of said head portion, this portion of said catch means engaging said cover member being made of wire.

7. In a staple tacker, a frame having an elongated chambered head portion for the reception of staple driving mechanism, the lower end section of said head portion being of forwardly opening channel shape in cross section to receive and to guide the lower portion of the staple driving mechanism, whereby the lower end section of the chamber of said head portion is open at its front, a channel-shaped front cover member for the lower end section of said chamber and having slidable telescopic straddling association with the channel-shaped lower end section of said head portion, said cover member and said head portion section having longitudinally disposed interlocking ribs whereby the telescopic straddling association of said cover member with said head portion section can be effected only by endwise

slidable movement of the cover member relative to said head portion section, and means connected to the frame and detachably connected to said cover member for releasably securing it against longitudinal movement the cover member to said head portion section.

8. In a staple tacker, a frame having an elongated chambered head portion for the reception of staple driving mechanism, the lower end section of said head portion being of forwardly opening channel shape in cross section to receive and to guide the lower portion of the staple driving mechanism, whereby the lower end section of the chamber of said head portion is open at its front, a channel-shaped front cover member for the lower end section of said chamber and having slidable telescopic straddling association with the channel-shaped lower end section of said head portion, said cover member being so formed that its telescopic straddling association with said head portion section can be effected only by endwise slidable movement of the cover member upwardly along said head portion section and its disassociation effected only by endwise slidable movement of the cover member downwardly along said head portion section, and means connected to the frame and detachably connected to said cover member for normally resisting downward slidable movement thereof relative to said head portion section to thereby releasably retain said cover member in telescopic straddling association with said head portion section.

9. In a staple tacker, a frame having an elongated chambered head portion for the reception of staple driving mechanism, the chamber of said portion being open at its front, upper and lower front cover members for said chamber, means for removably securing said upper cover member to said head portion, and means carried by the securing means for said upper cover member for removably securing the lower cover member to said head portion.

10. In a staple tacker, a frame having an elongated chambered head portion for the reception of staple driving mechanism, the chamber of said head portion being open at its front, upper and lower front cover members for said chamber, fastening elements for removably securing said upper cover member to said head portion, and means having detachable connection with said lower cover member for releasably securing such cover member to said head portion, the securing means for said lower cover member being secured to said head portion by the fastening elements for said upper cover member.

11. In a staple tacker, a frame having an elongated chambered head portion for the reception of staple driving mechanism, the chamber of said head portion being open at its front, upper and lower front cover members for said chamber, fastening elements for removably securing said upper cover member to said head portion, and means for removably securing said lower cover member to said head portion, the securing means for said lower cover member comprising a U-shaped spring having its side arm portions independently carried by said fastening elements for said upper cover member and having its lower cross or bridging portion releasably seated beneath a retaining abutment of said lower cover member.

12. In a staple tacker, a frame having an elongated chambered head portion for the reception of staple driving mechanism, the chamber of said

head portion being open at its front, upper and lower front cover members for said chamber, means for removably securing said upper cover member to said head portion, said lower cover member and head portion having ribs extending generally in the direction of staple driving mechanism movement to provide longitudinal telescopic association between said lower cover member and said head portion, and means for removably securing against longitudinal movement of said lower cover member to said head portion, the securing means for said lower cover member being retained in assembly with said head portion by the securement to said head portion of said upper cover member.

13. In a staple tacker, a frame having an elongated head portion of channel shape in cross section, the channel side walls extending forwardly and providing the side walls of a chamber open at its front for the reception of staple driving mechanism, upper and lower front cover members of channel shape in cross section for forming the front portion of said chamber, means for removably securing the upper cover member to the head portion with the side walls of such cover member extending rearwardly and in alignment with the head portion side walls, whereby the upper end section of the staple driving mechanism receiving chamber formed by the channels when the upper cover member is secured to the head portion is of greater depth than the channel in said head portion, said head portion being provided below said upper cover member with forwardly extending side wall extensions which increase the depth of the lower end section of the chamber approximately to that of the upper end section of the chamber as afforded by the securement of the upper cover member, and means for removably securing the lower cover member to said head portion in telescopic association with its side wall extensions.

14. In a staple tacker, a frame having an elongated head portion of channel shape in cross section, the channel side walls extending forwardly and providing the side walls of a chamber, open at its front, for the reception of staple driving mechanism, upper and lower front cover members of channel shape in cross section for said chamber, means for removably securing the upper cover member to said head portion with the side walls of said cover member extending rearwardly and in alignment with the head portion side walls, whereby the upper end section of the head portion chamber is increased in depth by the securement of the upper cover member to the head portion, said head portion being provided below said upper cover member with forwardly extending side wall extensions which increase the depth of the lower end section of the head portion chamber to that of the upper end section of the chamber as afforded by the securement of the upper cover member, and means secured to said head portion above the lower cover member for removably securing the lower cover member to said head portion in telescopic association with its side wall extensions.

15. In a staple tacker, a frame having an elongated chambered head portion, a plunger and a staple driving blade carried thereby mounted in the chamber of said head portion for reciprocatory movement, said chamber being open at its front, upper and lower front cover members for said chamber, means for removably securing said upper cover member and means for removably securing said lower cover member to said head

portion, and a relatively thin guiding and bearing strip for said plunger and said staple driving blade, said guiding and bearing strip being interposed between the front faces of said plunger and said staple driving blade and the rear surfaces of the upper and lower cover members.

16. In a staple tacker, a frame having an elongated chambered head portion, a plunger and a staple driving blade carried thereby mounted in the chamber of said head portion for reciprocatory movement, said chamber being open at its front, upper and lower front cover members for said chamber, means for removably securing said upper cover members and means for removably securing said lower cover member to said head portion, and a relatively thin guiding and bearing strip for said plunger and said staple driving blade, said guiding and bearing strip being interposed between the aligned front faces of the plunger and the staple driving blade carried thereby and the generally aligned rear surfaces of the upper and lower cover members, said upper cover member being provided with stop means for endwise movement of said guiding and bearing strip in an upward direction and said lower cover member being provided with stop means for endwise movement of such strip in a downward direction.

17. In a staple tacker, a frame having an elongated chambered head portion for the reception of staple driving mechanism, the upper end section of the chamber of said head portion being open at its front and at its top, a cover member, and means removably securing said cover member to said head portion for closing the front and the top of the upper end section of said chamber, said upper cover member being longitudinally interlocked against longitudinal movement in either direction with said head portion by interlocking portions integrally formed on said upper cover member and head portion separate from and independent of the means by which said cover member is removably secured to said head portion.

18. In a staple tacker, a frame having an elongated head portion of channel shape in cross section, the channel side walls extending forwardly and providing a chamber open at its front and at its top for the reception of staple driving mechanism, upper and lower cover members, means removably securing said cover members to said head portion for closing the front of the chamber thereof, said upper cover member being provided at its upper end with a rearwardly extending portion projecting into the channel-shaped top section of said head portion for closing the top of the chamber thereof, and means for longitudinally interlocking against movement in either longitudinal direction the rearwardly extending portion of said upper cover member with said head portion.

19. In a staple tacker, a frame having an elongated chambered head member portion for the reception of staple driving mechanism, the upper end section of the chamber of said head member being open at its front and at its top, a cover member removably secured to said head member for closing the front and the top of the upper end section of said chamber, and two separate and independent means for longitudinally interlocking said members, one of said means including a shoulder on one of said members and an interlocking extension on the other of said members.

20. In a staple tacker, a frame having an elongated chambered head portion for the reception

of staple driving mechanism, the lower end section of the chamber of said head portion being open at its front, a front cover member for the lower end section of said chamber, and spring catch means on said head portion straddling said cover member and being detachably engaged therewith for releasably securing said cover member to said head portion.

21. In a staple tacker, a frame having an elongated chambered head portion, a staple driving mechanism in said chambered head portion, the lower end section of said chamber being of forwardly opening channel shape in cross section with an open front and with the lower portion of said staple driving mechanism wholly received and guided therein, a channel-shaped front cover member for the lower end section of said chamber and having slidable telescopic straddling association with the channel-shaped lower end section of said head portion for closing said open front while having means for guiding the front of the lower portion of said staple driving mechanism, said cover member being so formed that its telescopic straddling association with said head portion section can be effected only by endwise slidable movement of the cover member upwardly along said head portion section and its disassociation effected only by endwise slidable movement of the cover member downwardly along said head portion section, and means connected to the frame and detachably connected to said cover member for releasably securing against longitudinal movement the cover member to said head portion section.

22. In a staple tacker, a frame having an elongated chambered head member for the reception

- 5 at its top, a cover member removably secured to said head member for closing the front and the top of the upper end section of said chamber, and means for longitudinally interlocking said members together including a lug on one of said members interlocking in a recess on the other of said members with dimensions corresponding to said lug.

HAROLD S. HELLER.
